LOCKING CLIP

Ralph W. Pritchard, Jr., Chicago, Ill.

Application April 16, 1947, Serial No. 741,709

2 Claims. (Cl. 24—11)

1

The present invention relates, generally, to a safety clip for an article such as pen, pencil, pocket thermometer, pocket slide rule, etc., having such a locking action that attempted removal of the article from a pocket tends to increase the locking action unless the release mechanism is operated. The invention relates particularly to such a safety clip which has the conventional appearance of ordinary pen and pencil clips now in use.

As indicated, the primary object of the invention is the provision of a safety clip for pocket articles, particularly pens and pencils, which has a conventional appearance and provides increased locking resistance as an attempt is made to remove such an article unless the safety clip is released.

Other objects of the invention, will, in part, be obvious and will, in part, appear hereinafter.

I am aware that safety clips for pens and pencils and similar articles have been previously made and proposed. It is desirable that these safety clips be of a type wherein attempted removal of the article from the pocket tends to increase the locking action, unless the safety clip is released. However, I am not aware that a safety clip of this type has been previously suggested or made available having a conventional appearance.

It is a very important feature that a safety clip has a pleasing and conventional appearance, particularly when applied to pens and pencils, otherwise it will not be accepted. Safety clips of this type, although applicable to any type of pocket article, have particular application to the more expensive pens and pencils. It is in connection with the latter articles that appearance is a very important factor and mere function alone is not sufficient to make a safety clip acceptable in connection with these items.

For a more complete understanding of the nature and scope of the present invention, reference may now be had to the following detail description of a preferred embodiment thereof, taken in connection with the accompanying drawings, wherein:

Figure 1 is a fragmentary front elevational view of the cap of a pen equipped with a safety clip forming a preferred embodiment of the present invention with the pen cap being shown clipped to a pocket front;

Figure 2 is a view, partly in section, taken on line 2—2 of Figure 1;

Figure 3 is a view similar to Figure 2 but show-

2

ing the safety clip mechanism in the released condition; and

Figure 4 is an enlarged inside elevational view of the lower end of the safety clip.

In the drawings, the reference character 5 designates, generally, a pen, which it will be understood is illustrative of any other object which is normally carried in the pocket, such as a pencil, thermometer, slide rule, etc. The pen 5, is shown 10 clipped to a pocket front 6 such as may be found on a vest pocket, a shirt pocket, coat pocket, or any other thin piece of material.

The pen 5 is provided with a safety clip indicated, generally, at 7. The safety clip 7 comprises a stationary clip member 8 having an integrally formed ferrule 10 at its upper end which is secured around the top of the pen 5 at the shoulder 11. The ferrule 10 may be crimped or friction fitted in place. The stationary clip member 8 also has a clip portion 12 which extends down the side of the pen 5 and is spaced therefrom so as to permit free entry and withdrawal of the pocket front 6.

The clip portion 12 is concave or C-shaped in cross-section and has an enlarged lower end 13 provided with a suitably smooth rounded edge 14 so as to guide the pocket front 6 underneath the clip.

The enlarged end 13 also serves as a housing 30 for a pawl member 15 having a prong portion 16. The pawl 15 is pivoted within the lower end of the clip portion 12 by a pin 17 extending through opposite sides of the enlarged end 13. The pawl 15 is so disposed that the prong portion 16 points 35 or extends upwardly and inwardly toward the main body of the pen 5.

In order to actuate the pawl member 15, an actuating arm 18 is provided which fits within the stationary clip member 8. At its lower end, 40 the actuating arm 18 is bifurcated as shown in Figure 4 so as to fit over or straddle the pawl member 15. The lower end of the actuating arm 18 is pivotally connected to the pawl member 15 by the pin 20 extending therethrough (Figure 2) so that the pin 17 serves as a fulcrum for the pawl 15.

At its upper end, the actuating arm 18 is connected with a plunger member 21 which may be a metal stamping or a plastic button which fits within a cavity 22 formed in the upper end of the cap of the pen 5. The actuating arm 18 may be connected to the plunger 21 by spot welding as indicated at 23. A vertical slot 24 is cut in the side wall of the cavity 22 so as to allow movement of the actuating arm 18 therein.

In order to normally bias or push the plunger member 21 to its upper or outer position, a coil spring 25 is provided within the cavity 22 so as to push up against the inside of the plunger 21. The plunger 21 may be depressed against the force of the spring 25 by application of pressure by the thumb or finger. The ferrule 10, secured to the cap at the shoulder 11, serves to retain the assembly in place. Upward movement of the plunger 21 is limited by the resistance offered to the movement of the pawl prong 16 by the main body of the pen 5.

In operation, the spring 25 normally maintains the pawl member 15 in its locked position, as shown in Figure 2. That is, the spring 25 forces or biases the plunger 21 in its upper position thereby tending to lift the actuating arm 18. Upward movement of the actuating arm 18 rotates the pawl 16 in a clockwise direction around the pin 17, thereby forcing the prong 16 into the pocket front 6. The spring 25 normally holds the prong 16 in this locked position. It will be seen that if an attempt is made to lift the pen 5 out of the pocket, when the prong 16 is in the locked position, the pulling action tends to cause the point of the prong 16 to bite into the pocket front 6 with increased locking action.

Depression of the plunger 21 by the thumb or finger against the force of the spring 25, lowers the actuating arm 18 thereby rotating the prong 16 away from the pocket front 6 and main body of the pen 5. The unlocked or released position of the safety clip part is shown in Figure 3 of the drawings.

The moving parts of the safety clip are not visible and the safety clip has a conventional appearance.

Since the invention may take the form of various specific embodiments, it will be understood that the one embodiment described hereinabove and shown in the accompanying drawings, is to be interpreted as illustrative and not in a limiting sense.

What is claimed as new is:

1. A safety clip for an article such as a pen or pencil, which comprises in combination, a stationary clip member having an attachment portion for securing to said article adjacent the top thereof and having a clip portion extending down the side of said article and spaced therefrom so as to permit a pocket front to slip freely between said stationary clip member and said article, a pawl member pivotally attached to the lower end of said stationary clip member so that the prong portion of said pawl is directed upwardly and inwardly toward said article and

may be moved into and out of engagement with a pocket front, an actuating arm fitting within said stationary clip member, the lower end of said actuating arm being pivotally connected to said pawl member so that vertical movement of said pawl member causes said actuating arm to actuate said pawl member, a plunger member mounted on the upper end of said article, a spring in the upper end of said article normally biasing said plunger in an outward position, and means interconnecting the upper end of said actuating clip arm with said plunger; said pawl prong being normally biased into locking engagement with a pocket front and being released from said locking engagement upon depression of said plunger.

2. A conventionally appearing safety clip for an article such as a pen or pencil, which comprises in combination, a stationary clip member having an integrally formed ferrule at its upper end secured around the top of said article and having a clip portion extending down the side of said article and spaced therefrom so as to permit free entry and withdrawal of a pocket front in between said clip portion and said article, said clip portion being C-shaped in cross-section with the sides being turned in toward said article, a pawl member pivotally attached within the lower end of said clip portion so that the prong portion of said pawl is directed upwardly and inwardly toward said article and is free to be moved into and out of engagement with a pocket front, an actuating arm fitting within said clip portion, the lower end of said actuating arm being pivotally connected to said pawl member so that upward movement of said actuating arm pivots said pawl member so as to move said prong portion into locking engagement with a pocket front while downward movement of said actuating arm pivots said pawl member so as to move said prong portion away from a pocket front, the upper end of said article having a cavity formed therein with a vertical slot in the wall thereof, a plunger member fitting within said cavity, a coil compression spring in said cavity and fitting underneath said plunger so as to normally bias the latter toward its outermost position, said actuating arm having an integral connecting portion on its upper end fastened to said plunger and slidably in said slot, said pawl prong being normally biased into locking engagement with a pocket front and being releasable from said locking engagement upon depression of said plunger.
